BLOWERS

John R. Thygesen, Abington Township, Pa., assignor to Proctor & Schwartz, Inc., Philadelphia, Pa., a corporation of Pennsylvania

Application August 11, 1954, Serial No. 449,181

7 Claims. (Cl. 230—114)

The present invention relates to centrifugal blowers and has particular application to blowers of this type for directing air against or through material in a drying chamber. This application is a continuation-in-part of the application filed May 25, 1953, Serial No. 357,126, now abandoned, entitled Improvements in Blowers.

Prior to the present invention, centrifugal blowers have conventionally been of the scroll type. The conventional scroll-type blowers, however, have not been entirely satisfactory for drying chambers since the blower exhausts a column of air in which the pressure varies substantially across the column. This variable pressure is not predeterminable since it is not regular and since the high pressure zones in the air column shift laterally as the impeller speed is changed. As a result, the air column does not dry the material in the chamber uniformly, the material in the high pressure and velocity zones being dried more rapidly than the material in the low pressure zones. Therefore, it is necessary to retain the material in the chamber until that portion exposed to the low pressure zone is completely dried, and frequently the remaining portion of the material becomes overdried and damaged.

In order to partially compensate for the varying pressure in the column of air exhausted by the blower, it has been customary to provide baffles for directing the air onto the material to be dried. This method of compensation is not completely satisfactory since the positioning of the baffles is effective for only one rotary speed of the blower impeller and to locate the baffles properly, it is necessary to run a series of tests to determine the exact pressure and velocity distribution across the mouth of the blower. In addition, the prior blowers do not operate at maximum efficiency because there is a certain amount of leakage of air from the high pressure side of the impeller into the low pressure intake thereof. As a result of this leakage there is a circulation of air about the blower impeller which may also contribute to the varying pressure across the mouth of the blower.

With the foregoing in mind, a principal object of the present invention is to provide a blower which has a uniform pressure distribution across its mouth.

A further object of the invention is to provide increased efficiency through the reduction of friction and leakage losses.

Another object of the invention is to provide a blower construction which eliminates the requirement for specially constructed scroll casings.

Still another object is to provide a blower having a simple adjustment to provide optimum efficiency upon regulation of the impeller speed.

A still further object is to provide a novel blower for drying chambers and the like having two diametrically opposed outlet orifices and a single impeller for discharging the drying medium through said orifices.

These and other objects of the invention and the various features and details of the construction and operation

2

thereof are more fully set forth hereinafter with reference to the accompanying drawing in which:

Fig. 1 is a side elevational view of a blower as seen from the suction side thereof with a portion of the casing broken away to illustrate the operation of the device;

Fig. 2 is a vertical sectional view taken on the line 2—2 of Fig. 1, and

Fig. 3 is a side elevational view of a modified form of blower having its side cover plate removed.

The present invention contemplates a blower which provides a uniform distribution of pressure across its outlet opening. The casing surrounding the rotary impeller is generally rectangular and is provided with a cut-off plate projecting into close proximity to the outer peripheral surface of the impeller. Rotation of the impeller causes a predetermined air flow within the casing which assumes a scroll-like path starting at a point adjacent the cut-off plate and gradually increasing in width until it extends laterally across the outlet opening. The air pressure across the opening is constant and, therefore, expels a column of air having uniform pressure and velocity across its width.

Referring more particularly to the drawing, the blower illustrated in Figs. 1 and 2 comprises a narrow rectangular casing 11 defining a rectangular air chamber closed on the bottom and all four sides and having an open upper end 12 therein which provides an outlet opening in the casing. Mounted adjacent the lower corner of the casing and extending substantially between the opposite side walls thereof is a standard axial-inlet, radial-exhaust vane type impeller 13 which draws air axially through an inwardly flared opening 14 in the side wall of the casing and forces the air radially outward into the interior of the casing. The impeller is rotatably mounted on the side wall of the casing opposite to the flared inlet opening 14 and is driven, for example, by means of an electric motor 15.

The impeller 13 is of conventional construction comprising opposed radial walls 16 and 17 having mounted therebetween a plurality of vanes 18 for expelling the air into the interior of the casing 11. The forward radial wall 17 of the impeller is annular in form and the inner peripheral surface thereof defines the eye 19 of the impeller which constitutes the axial inlet thereof. The eye 19 corresponds in size to the inwardly flared opening 14, and is positioned in axial alignment therewith to provide an unimpeded air inlet for the blower. It should be noted that the forward wall of the impeller is closely adjacent the stationary inlet opening 14 so as to reduce to a minimum the clearance which permits air leakage into the inlet opening from the interior of the chamber defined by the casing.

In accordance with the present invention, the direction of the flow of air in the casing is controlled to provide an equal air pressure and velocity distribution across the length and the width of the casing outlet opening 12. To this end, a cut-off plate 21 is mounted adjacent one side of the casing outlet opening 12 for pivotal movement about an axis parallel to the axis of the impeller 13. The cut-off plate is mounted on a shaft 22 which is journaled between the side walls of the casing in the junction between the open upper end 12 and the adjacent end wall of the casing 11. The cut-off plate 21 depends downwardly and inwardly into close proximity with the outer peripheral surface of the impeller 13 in a generally radial direction thereto, and extends laterally the full width of the casing, and is exposed to air in said chamber at both sides of said plate.

Means is provided to adjust the position of the plate 21, and to this end, a crank 23 is keyed to the shaft 22 and mounts a plunger 24 operable to engage in one of a series of detents 25 on the forward wall of the casing. The cut-off plate 21 is adjustable to obtain optimum ef-

iciency in accordance with the rotary speed of the impeller, and the detents 25 are positioned in accordance with the various rotary speeds of the motor 15.

The operation of the impeller 13 discharges the air under pressure into the interior of the casing 11 where it is expelled through the outlet opening 12 in a column having uniform pressure and velocity distribution across its width. The air flow in the casing follows a scroll-like path starting from a point adjacent the junction of one side of the cut-off plate and the impeller and gradually increasing in width until it extends entirely across the outlet opening 12 where it is discharged. This scroll-like path is determined by the pressure of the air within the casing which builds up a cushion of air about the interior walls of the casing in accordance with the most efficient path for the air flow. Since the path is determined primarily by the air pressures and only secondarily by the walls of the casing, there is relatively low friction loss between the air current and the stationary walls. The efficiency of the blower is, therefore, substantially increased. The air pressure built up adjacent the other side of the cut-off plate 21 when the plate is properly positioned, provides a uniform pressure and velocity distribution across the width of the opening 12. Since the path of the air flow and the pressures in the casing change in accordance with the rotary speed of the impeller, it is desirable to adjust the cut-off plate 21 to compensate for the changes to provide optimum efficiency. If desired, the detents 25 may be calibrated to correspond with given rotary speeds of the motor so as to provide simple adjustment of the cut-off plate upon regulation of the rotary speed of the impeller.

To further increase the efficiency of the blower, circulation of the air from the pressure zone interiorly of the casing in the suction zone in the inlet opening of the impeller is prevented by providing a plurality of auxiliary blades 26 spaced circumferentially about the forward annular wall 17 of the impeller. The blades 26 project axially beyond the forward wall of the impeller and surround the inwardly flared opening 14. These blades effect a pressure drop adjacent their inner edges and effectively preclude leakage of air through the clearance between the forward wall 17 of the impeller and the inlet opening 14.

A modified form of the invention is shown in Fig. 3 wherein a casing 31 forms a rectangular air chamber having its opposite side walls 32, 32 open for the discharge of a column of air. In this form of the invention, an impeller 33 similar in detail to the impeller 13 is provided intermediate the end walls of the casing 31. A motor (not shown) drives the impeller to effect the discharge of the air from the casing. As in the previously described embodiment, the front side wall which is removed in Fig. 3 is provided with a flared opening similar to the opening 14.

In this embodiment of the invention, two cut-off plates 35, 35 are provided at diagonally opposite corners of the casing. Each plate is mounted on a shaft 36 and is journaled in the casing 31 at the junction of the open side wall 32 and the end wall. A crank (not shown) is provided to adjust the angularity of each cut-off plate 35. As in the previous embodiment, the angular position of the cut-off plate may be calibrated in accordance with the rotary speeds of the impeller to provide optimum efficiency of the blower.

This form of the invention operates similarly to the above-described embodiment so as to discharge a column of air from the open side 32 having uniform pressure distribution across its width. The invention eliminates the necessity for a scroll-type casing and affords the use of a simple rectangular box-like structure. Thus, the cost of the blower is substantially reduced while maintaining optimum efficiency.

From the foregoing description, it is seen that the present invention provides a blower simple in construc-

tion, having uniform pressure and velocity distribution across its outlet opening, and in which the losses due to friction and leakage have been substantially eliminated.

While particular embodiments of the invention have been herein illustrated and described, it is not intended to limit the invention to such disclosures, and changes and modifications may be made therein and thereto within the scope of the following claims.

I claim:

1. A centrifugal blower comprising a generally rectangular casing having one side open for exhausting a column of air, a vane-type impeller having a central eye and mounted for rotation in said casing about an axis substantially parallel to said open side and adjacent one end wall of the casing, means in said casing defining inwardly-flared walls of an air inlet aperture in registry with the eye of said impeller, a plurality of generally axially disposed blades spaced circumferentially about said impeller, and projecting axially so as to surround said inwardly flared walls, said blades being operable upon rotation of said impeller to reduce the pressure within said casing at the opposite side of said flared walls from said inlet opening, and a cut-off plate extending substantially from the junction between said open side and said one end wall of the casing and terminating in close proximity to said impeller whereby upon rotation of said impeller a column of air is exhausted from the eye of the impeller through said open side.

2. A centrifugal blower comprising a generally rectangular casing having opposite sides open from exhausting columns of air, a vane-type impeller having a central eye and mounted for rotation in said casing about an axis substantially parallel to said open sides and adjacent opposite end walls of the casing, means in said casing defining inwardly-flared walls of an air inlet aperture in registry with the eye of said impeller, a plurality of generally axially disposed blades spaced circumferentially about said impeller, and projecting axially so as to surround said inwardly flared walls, said blades being operable upon rotation of said impeller to reduce the pressure within said casing at the opposite side of said flared walls from said inlet opening, and cut-off plates, one extending substantially from the angle between one open side and one end wall of the casing and terminating in close proximity to said impeller and the other extending substantially from the angle between the opposite open side and the opposite end wall and terminating in close proximity to said impeller whereby upon rotation of said impeller columns of air having a uniform pressure distribution across their width are exhausted from the eye of the impeller through said open sides.

3. A centrifugal blower comprising a casing forming a generally rectangular air chamber having one side open for exhausting a column of air, a vane-type impeller having a central eye, said impeller being mounted for rotation in said casing about an axis substantially parallel to said open side and adjacent one end wall of the casing, means defining an air inlet to the eye of said impeller, and a cut-off plate extending substantially from the junction between said open side and said one end wall of the casing and terminating in close proximity to said impeller and being exposed to air in said chamber on both sides of said plate whereby upon rotation of said impeller, the vanes of said impeller exhaust a column of air from the eye of the impeller outwardly through said open side.

4. A centrifugal blower comprising a generally rectangular casing having opposite sides open for exhausting a column of air, a vane-type impeller having a central eye, said impeller being mounted for rotation in said casing about an axis substantially parallel to said open sides and adjacent opposite end walls of the casing, means defining an air inlet to the eye of said impeller, a cut-off plate extending substantially from the junction between one open side and one end wall of the casing and ter-

minating in close proximity to said impeller and a second cut-off plate extending substantially from the junction between the opposite open side and the opposite end wall of the casing and terminating in close proximity to the impeller, whereby upon rotation of said impeller columns of air having a uniform pressure distribution across their width are exhausted from the eye of the impeller through said open sides.

5. A centrifugal blower comprising a generally rectangular casing having one side open for exhausting a column of air, a vane-type impeller having a central eye, said impeller being mounted for rotation in said casing about an axis substantially parallel to said open side and adjacent one end wall of the casing, means defining an air inlet to the eye of said impeller, an adjustable cut-off plate extending substantially from the junction between said open side and said one end wall of the casing and terminating in close proximity to said impeller whereby upon rotation of said impeller a column of air having uniform pressure distribution across its width is exhausted from the eye of the impeller through said open side, and means to adjust the angular position of said cut-off plate in the junction between said open side and said one end wall.

6. A centrifugal blower comprising a generally rectangular casing having one side open for exhausting a column of air, a vane-type impeller having a central eye, said impeller being mounted for rotation in said casing about an axis substantially parallel to said open side and adjacent one end wall of the casing, means defining an air inlet to the eye of said impeller, a shaft journaled in the casing in parallelism with the axis of said impeller in the junction between said open side and said one end wall of the casing, an adjustable cut-off plate mounted on said shaft and extending and terminating in close proximity to said open side and said one end wall of the casing, whereby upon rotation of said impeller a column of air having uniform pressure distribution across its width is exhausted from the eye of the impeller through said open side, and means to adjust the angular position of said cut-off plate in the junction between said open side and said one end wall.

mity to said impeller whereby upon rotation of said impeller a column of air having a uniform pressure distribution across its width is exhausted from the eye of the impeller through said open side, and means to adjust

5 the angular position of said shaft comprising a handle keyed to said shaft, means defining a plurality of detents in said casing, and a plunger mounted on said handle and operative to selectively engage said detents to thereby positively position said cut-off plate angularly relative to said impeller.

10 7. A centrifugal blower comprising a generally rectangular casing having one side open for exhausting a column of air, a vane-type impeller having a central eye, said impeller being mounted for rotation in said casing about an axis substantially parallel to said open side, drive means for rotating said impeller, means defining an air inlet to the eye of said impeller, and a cut-off plate extending substantially from the junction between said open side and one end wall of the casing and terminating

15 in close proximity to said impeller substantially radial thereto whereby upon rotation of said impeller a column of air is exhausted from the eye of the impeller through said open side, and means for adjusting the angular position of said cut-off plate from said junction in accordance with the rotary speed of said drive means.
